[57] CLAIM

The ornamental design for a clamping jaws, as shown and described.

DESCRIPTION

FIG. 1 is a front elevational view of a clamping jaws showing my new design;

FIG. 2 is a right side elevational view;

FIG. 3 is a top plan view;

FIG. 4 is a top, front and left-side perspective view; and,

FIG. 5 is a bottom rear and right side perspective view thereof.

The broken line showing of the vise grips are for illustrative purposes only and forms no part of the claimed design.

FIG. 3

FIG. 1

FIG. 2
